UNITED STATES PATENT OFFICE.

CHARLES W. PETERSON, OF ANN ARBOR, MICHIGAN.

DESIGN FOR A LOUD SPEAKER.

Application filed May 1, 1925. Serial No. 13,270. Term of patent 14 years.

To all whom it may concern:

Be it known that I, CHARLES W. PETERSON, a citizen of the United States, residing at Ann Arbor, in the county of Washtenaw and State of Michigan, have invented a new, original, and ornamental Design for Loud Speakers, of which the following is a specification, reference being had to the accompanying drawing, forming part thereof.

In the drawing:

Figure 1 is a back perspective view.

Figure 2 is a side elevation of the loud speaker showing my new design.

I claim:

The ornamental design for a loud speaker as shown.

CHARLES W. PETERSON.
